CHARLES H. MEIGS, OF PHILADELPHIA, PENNSYLVANIA, AND FRANK A. EPPS, OF NEW YORK, N. Y., ASSIGNEES TO MACANDREWS & FORBES COMPANY, OF CAMDEN, NEW JERSEY, A CORPORATION OF NEW JERSEY.

FIRE-EXTINGUISHING SYSTEM.

1,261,422.

Specification of Letters Patent.

Patented Apr. 2, 1918.

Application filed July 17, 1917. Serial No. 181,026.

To all whom it may concern:

Be it known that CHARLES H. MEIGS and FRANK A. EPPS, both citizens of the United States, residing at Philadelphia and New York, in the counties of Philadelphia and New York and States of Pennsylvania and New York, have invented new and useful Improvements in Fire-Extinguishing Systems, of which the following is a specification.

This invention relates to improvements in fire-extinguishing systems, pertaining more particularly to systems of the sprinkler-head type, especially where employed in connection with systems operating on the foam-extinguishing principle.

The foam-extinguishing process of extinguishing fires is particularly adapted for use in connection with tanks, etc., containing inflammable fluids as well as in other relations, and various ways of utilizing the system have been contemplated and employed. These systems generally employ two solutions which, when brought together, com- mix and form a compound which produces fumes non-supporting to combustion.

As shown, for instance, in the patents to Walker, Nos. 1,186,249 and 1,186,251, it is a general practice to carry the solutions through independent conduits to a location adjacent to the point where the compound is to be produced and used. This practice is employed for the reason that the compound is of a comparatively rapid development when the solutions are brought together, remaining in this state for a period and then gradually deteriorating with respect to the foam action, it being understood, of course, that maximum efficiency is present where the several solutions are thoroughly commixed, the rapidity of development depending somewhat on the manner in which the solution streams are caused to commix. For instance, in the form shown in said patents, the solution streams are introduced into a commixing head where development takes place and the foam compound produced is permitted to pass to the point of use through a comparatively short passage-way which practically offers no restriction to the free passage of the foam compound.

The structures disclosed in these patents therefore provide for the development of the compound outside of the tank which is being protected, the foam produced "welling up" 55 and passing over a ledge onto the surface which is to be acted upon and, so far as we are aware, this is the general practice with respect to the delivery of extinguishing compound onto such surface, the structures, in 60 some cases, however, having the commixing chambers in a separate compartment within the tank.

In the present invention, the general purpose is to develop the compound practically 65 at the point of use. For instance, if employed in connection with tanks, the development occurs within the tank portion where the inflammable fluid is located, the streams being delivered in opposition to 70 each other so that the integrity of each stream is broken down by its contact with the opposing stream, thus causing an intimate commixture of the component streams at a point or points over the surface of the 75 fluid, thus rapidly developing the compound at a point where it is immediately effective.

Since this practically requires that the streams be properly directed to their common meeting point, and that the nozzle or 80 sprinkler-head structure be located within the tank and subject to the temperatures developed by the fire conditions therein, it is desirable that the structure employed for delivering the solution be of such form as to 85 insure the proper delivery of the streams under all conditions.

This result is obtained by the use of a nozzle or sprinkler-head structure which is practically unitary in form and so arranged 90 that the effects of the heat will not affect the direction of flow of the streams into commixing positions. At the same time, the structure carries an automatic releasing means which can be easily and simply in- 95 stalled at any time.

To these and other ends, the nature of which will be readily understood as the invention is hereinafter disclosed, the invention consists in the improved construction 100 and combination of parts hereinafter fully described and illustrated in the accompany-

ing drawings, and more particularly pointed out in the appended claims.

In the accompanying drawings, in which similar reference characters indicate similar parts in each of the views:

Figure 1 is a sectional view of a preferred embodiment of the present invention, the sprinkler-head being shown as mounted in a tank.

Fig. 2 is an end elevation of the sprinkler-head.

For the purpose of illustrating the present invention, we have shown the nozzle or sprinkler-head structure as employed in connection with a tank for inflammable fluids, a tank wall being indicated at A.

The sprinkler-head embodies a casing 10 having two conduits 11, the walls of which are connected by a suitable web structure 12, 20 the inner wall portions of the conduits extending approximately parallel to each other, each conduit preferably decreasing in cross-sectional area as it advances from its rear end, indicated at 13, thus producing a 25 passageway of gradually decreasing cross-sectional area toward the point of exit. The sprinkler-head is connected up to independent supply lines 14 by suitable unions or couplings 15, each supply line leading from 30 a suitable solution receptacle, not shown.

The advance ends of the conduits are each formed with a normally closed discharge opening. This opening is formed by tapping the inner wall of the conduit adjacent 35 its advance end to provide an opening 16 having a seat 17 and a threaded enlargement of the opening indicated at 18, thus providing opening 16 with portions on two diameters. The seat is adapted to receive an annular resilient metal member 19 having a 40 central opening 19^a, member 19 being secured in position by a threaded annulus 20, this arrangement restricting the actual discharge opening from the conduit to the area 45 of opening 19^a, although the area of opening 16 is considerably greater.

As shown in Fig. 1 opening 16 of one conduit is in axial alinement with the similar opening of the other conduit, so that when 50 solution discharge from the conduits is permitted through the alined openings 19^a, the streams are discharged in opposite directions and provide stream break-down within in the space between the opposing openings 55 16, the result being that the solutions will be rapidly placed in condition for commixture which will take place to a high degree, thus rapidly developing the foam compound.

These openings 19^a are normally closed by 60 a suitable closure of the automatic type, the form shown in the drawing indicating glass members 21, each having a face adapted to close the opening, each member 21 being carried by a holder 22. Holders 22 are joined by an element 23 which holds mem-

bers 21 to their seats on members 18, said element, however, being arranged to break this holding effect in the presence of fire conditions. The holding structure shown is of a well-known type useful for this purpose. 70

With the parts in the position shown in Fig. 1, the several solution streams are kept from passing out of their respective conduits 11. When, however, the release device is affected by fire conditions and thus eliminates the holding action on members 21, said members 21 will pass out of closing position, either by the action of the releasing device itself or by pressure from within the conduits, or both, thereby simultaneously opening each conduit for the discharge of its solution. 75

To permit a ready positioning of members 19, we preferably form threaded openings 24 in the outer walls of the conduits, openings 24 being axially alined with openings 16. Openings 24 are closed by suitable caps or plugs 25. As will be seen, opening 24 is of greater diameter than opening 18, the latter in turn being of greater diameter than 80 opening 16, all of these openings, however, being axially alined. Obviously, this arrangement permits of the formation of openings, etc., by simple machining operations. 90

By removing plug 25, access is readily had to annulus 20 to remove the latter and thus permit removal of member 19, a reversal of these operations, with member 19 on its seat, restoring the structure to normal conditions. 100 While this arrangement affords a simple method of positioning members 19, either initially or at a time of renewal, without requiring detachment of the sprinkler-head from the connections, it also permits, when 105 desired, the ready installation of a prepared releasing device, viz: a device which is in complete form before being installed in the sprinkler-head. This action may be provided by removing the plug 25, annulus 20 110 and member 19 of one of the conduits, then positioning the releasing device in contact with member 19 of the other conduit, after which these removed elements are restored to position and set, the structure then being 115 ready for use.

As will be seen, the body of the structure is unitary and may be readily cast. Obviously, the web structure 12 will prevent any possibility of the discharge openings 120 passing out of axial alinement, either through manual manipulations or by the action of heat where the structure is placed in a position where it is necessarily in close proximity to high temperatures. 125

It will be clear that the general arrangement is such as to be simple and efficient in operation, durable in construction and capable of production at a relatively low cost. In addition, renewals can be provided in a 130

simple and efficient manner. And since the structure provides for rapid development of the extinguishing compound at a point where it may be made immediately effective, 5 it will be understood that the general arrangement provides for maximum efficiency in operation.

While we have referred to the installation of the structure in connection with tanks, 10 thus illustrating its use under conditions of extreme hardship, it will be readily understood that the sprinkler-head structure can be employed in other types of installations, and we desire to be understood as not limiting 15 the invention to use in connection with tank structures.

While we have herein shown and described a preferred embodiment of the invention, it will be readily understood that 20 changes and modifications therein may be found desirable or necessary to meet the exigencies of use, and we desire to be understood as reserving the right to make any and all such changes or modifications, in so far 25 as the same may fall within the spirit and scope of the appended claims.

It is also to be understood that the invention is not to be limited to the specific structure of releasing device shown, since it 30 is obvious that any suitable form of release device or equivalent of members 19 may be employed.

Having thus described our invention what we claim as new, is:

1. In fire-extinguishing apparatus where-
in a plurality of normally-separated compo-
nent solutions are made active in the produc-
tion of an extinguishing compound by the
automatic release of the several solutions in
40 stream form in opposing directions to pro-
duce commixing of the component solutions,
a sprinkler-head carrying the releasing ele-
ment and connected to the solution supply
lines, said head comprising a body portion
45 having independent passageways for the sol-
utions, said passageways extending in sub-
stantial parallelism, the walls of said pas-
sageways carrying opposing openings axi-
ally aligned with the axes of the openings ex-
50 tending transverse to the direction of length
of the passageways, said openings permitting
discharges of the solutions individually in
stream form and in opposing directions, and
an automatic control element extending be-
55 tween and normally closing said openings,
said element being rendered active to release
the solutions in the presence of fire con-
ditions.

2. A sprinkler-head for fire extinguishing
60 systems of the character described, comprising
a body portion formed with a pair of
substantially parallel conduits spaced-apart
and integrally connected, each of said con-
duits having its advance end formed with
65 an opening having its axis transverse to the

direction of length of the conduit, the open-
ings of the several conduits facing each
other in axial alinement, removable resilient
members intersecting said openings, said
members having openings, and a closure de- 70
vice for closing the member openings, said
device being adapted to be rendered inactive
as a closure in the presence of fire conditions.

3. A sprinkler-head for fire extinguishing
systems of the character described, compris- 75
ing a body portion formed with a pair of
substantially parallel conduits spaced-apart
and integrally connected, each of said con-
duits having opposite walls of its advance
end formed with openings having a common 80
axis extending transverse to the direction of
length of the conduits, the inner openings
of the several conduits facing each other in
axial alinement, a removable resilient mem-
ber seated in and intersecting each inner 85
opening, said members provided with the
discharge openings for the conduits, remov-
able plugs for the outer openings, and clo-
sure means extending between said discharge
openings, said means being rendered inactive 90
as a closure in the presence of fire conditions.

4. In a sprinkler-head structure for fire
extinguishing systems, a body portion com-
prising a casting having a pair of substan- 95
tially parallel conduits spaced-apart and
connected by a web structure, each conduit
having opposite walls at its advance end
formed with openings having a common axis
extending transverse to the direction of 100
length of the conduit, the inner openings of
the several conduits facing each other in
axial alinement and each having its wall
formed on two diameters to provide a seat
for a removable element adapted to provide 105
the discharge opening of the conduit, each
seat facing the outer wall of the conduit and
extending on a plane intersecting the open-
ing, a removable annulus mounted in the
portion of greater diameter of such opening 110
for securing the element in position, and a
plug for closing the opening in the outer
wall of each conduit.

5. In a sprinkler-head structure for fire
extinguishing systems, a body portion com- 115
prising a casting having a pair of substan-
tially parallel conduits spaced-apart and con-
nected by a web structure, each conduit hav-
ing opposite walls at its advance end formed
with openings having a common axis extend- 120
ing transverse to the direction of length of
the conduit, the inner openings of the sev-
eral conduits facing each other in axial
alinement and each having its wall formed
on two diameters to provide a seat for a 125
removable element adapted to provide the
discharge opening of the conduit, each seat
facing the outer wall of the conduit and ex-
tending on a plane intersecting the opening,
a removable annulus mounted in the portion 130
of greater diameter of such open-

ing for securing the element in position, and a plug for closing the opening in the outer wall of each conduit, the space between the inner openings being unobstructed and adapted to receive the closure means for the several discharge openings.

In testimony whereof we have hereunto

set our hands in presence of two subscribing witnesses.
